FIG. 1 is a top plan view of a foot control for dental equipment showing my new design;

FIG. 2 is a side elevational view thereof;

FIG. 3 is a side elevational view thereof, and taken from the side opposite that shown in FIG. 2;

FIG. 4 is a bottom plan view thereof;

FIG. 5 is an enlarged sectional view taken along the line 5—5 of FIG. 1;

FIG. 6 is a greatly enlarged fragmentary sectional view taken along the line 6—6 of FIG. 1; and

FIG. 7 is an enlarged sectional view taken along the line 7—7 of FIG. 3.

My design for the foot control for dental equipment is characterized by the low profile, as best seen in FIGS. 2 and 3.

The dominant feature of my design resides in the portions shown in full line.

I claim:

The ornamental design for a foot control for dental equipment, substantially as shown and described.
